Primary Examiner — Terry A Wallace(74) *Attorney, Agent, or Firm* — Volpe and Koenig, PC(57) **CLAIM**

The ornamental design for a condiment holder, as shown and described.

DESCRIPTION

FIG. 1 is a perspective view of a condiment holder according to my new design;

FIG. 2 is a front elevational view of the design shown in FIG. 1;

FIG. 3 is a back elevational view of the design shown in FIG. 1;

FIG. 4 is a top plan view of the design shown in FIG. 1;

FIG. 5 is a bottom plan view of the design shown in FIG. 1;

FIG. 6 is a left side elevational view of the design shown in FIG. 1; and,

FIG. 7 is a right side elevational view of the design shown in FIG. 1.

The broken lines are for illustrative purposes only and form no part of the claimed design.
